DRAIN VALVE FOR AN AIR LINE FILTER

Wendell M. Dillon, North Andover, Mass., assignor to
Watts Regulator Company, Lawrence, Mass., a corporation of Massachusetts

Filed Aug. 24, 1959, Ser. No. 57,271

Term of patent 14 years

(Cl. D78—1)

FIGURE 1 is a top plan view of a drain valve for an air filter line, showing my new design.

FIGURE 2 is a side elevational view thereof.

FIGURE 3 is a bottom plan view of the same.

FIGURES 4 and 5 are end elevational views of the same taken respectively looking from the left and right of FIGURE 2.

I claim:

The ornamental design for the drain valve for an air line filter, substantially as shown.
